Atty.

UNITED STATES PATENT OFFICE.

HENRY M. WILLIAMSON, OF CHICAGO, ILLINOIS.

RADIO RECEIVING APPARATUS.

Application filed September 25, 1922. Serial No. 590,220.

To all whom it may concern:

Be it known that I, HENRY M. WILLIAMSON, a citizen of the United States, and a resident of the city of Chicago, in the county 5 of Cook and State of Illinois, have invented certain new and useful Improvements in Radio Receiving Apparatus, of which the following is a specification.

This invention is an apparatus having an 10 audio-frequency amplifier, or a cascade of such amplifiers, and having means for isolating and excluding from their telephonic receivers static and other wave disturbances, from any source, foreign to the amplified 15 sound waves transmitted thereto and for preventing oscillations in a thermionic amplifier.

The prime object of my invention, broadly stated, is to provide a radio apparatus with 20 means adapted to filter out static and other waves foreign to the audible sound waves, and thereby isolate the receiver therefrom and also to exclude the influences to which inherent internal undesired oscillations are 25 due.

A further object of my invention is to provide a means located between the detector and the receiver, which means is adapted to filter out static from desired sound waves.

With these ends in view, my invention finds embodiment in certain features of novelty in the construction, combination and arrangement of parts by which the said objects and other objects are attained, all as 35 hereinafter fully described with reference to the accompanying drawing and more particularly pointed out in the claims.

In said drawing is illustrated diagrammatically a radio apparatus in which my invention finds its embodiment.

Similar characters of reference indicate the same parts in said drawing.

Referring to the drawing, 1 is the antenna, 2 the primary winding of the loose-coupler 45 or vario-coupler, 3 the adjustable switch, and 4, a variable condenser approximately .001 m. f., while 5 represents a ground connection. This circuit is known as the "antenna" or open circuit, and, as is usual, is 50 capable of adjustment as to resonance for high frequency electro-magnetic waves of different lengths which are transmitted from a transmitting station. This adjustment simply means that a proper value of capacity (in micro-farads) and a proper value of in-

ductance (in henries) has been attained to allow the passage of waves of predetermined frequencies.

6 indicates the secondary winding of the induction coil, or vario-coupler. Connected to one terminal of this secondary winding is a grid condenser 7, a grid leak 8, and the grid 9 of the detector tube 10. The other terminal of the winding 6 is connected to the lighting filament 11 of the same tube. 65 Across the terminals of the secondary coil 6 is connected a variable condenser 6^a, of approximately .0005 m. f. This condenser effectuates sharper tuning of the circuit, which is known as the closed or detector circuit, by 70 giving the proper value of capacity to that circuit in order to counter-balance the inductance of the secondary winding of the vario-coupler, thereby allowing the high frequency waves to pass to and charge the grid alternately. The grid 9 in the tube 10 acts as a valve inasmuch as it accumulates charges of electricity alternating in direction, which charges alternately increase and decrease the resistance of the path between 80 the filament and the plate 12 for the plate circuit current, thereby causing corresponding increases and decreases in the current value of the plate circuit, in which circuit the primary winding 13 of a transformer or 85 induction coil is situated. The current for the plate circuit, including the primary winding 13, is furnished by a dry-cell battery of approximately 22 volts, shown at 14. This filament circuit contains a rheostat 15 90 for regulating the current flow from the six-volt storage battery 16, through the filament 11, through the space in the vacuum of the tube 10 to the plate 12, and thence through the primary winding of the transformer 13 95 to the battery 14. This space appears to be an "open", but the functioning of the tube is explained by the ionic action within the tube when the filament is heated to incandescence.

100 The condenser 17 shunted across the primary winding 13 of the transformer, assists in demagnetizing the core and the winding of the transformer, thereby making this winding more susceptible to high frequency 105 currents and making for clearness. In addition, this condenser offers a path of low resistance for very high frequency currents, such as are set up by static and other foreign interferences, shunting them out of 110

the primary winding of the transformer. It will be seen that the current in this plate circuit is of pulsating-direct character. The valve or grid 9, by causing a change of resistance in the ionic path between the filament and the plate, produces a corresponding change in the current in the plate circuit, but the current always flows in one direction.

10 18 represents the secondary winding of the transformer of which 13 is the primary. Transformers, such as are ordinarily employed, are usually 4 to 1 up to 10 to 1 ratio. The current flowing through the primary 15 13, induces into the secondary 18 a current of like character or form, but of higher pressure or voltage. This secondary current or voltage is impressed upon the grid 19 of the amplifying tube 20 and charges it with 20 greater intensity (alternately) than was the case in the previous tube, because now instead of being a feeble current, or pressure, and of very high frequency, this current is of audible frequency with a higher 25 pressure due to the fact that the 22 volt battery made it 22 volts pressure, and, in addition, the transformer "stepped" it up on a ratio of 4 to 1 or 10 to 1, or whatever ratio is employed, making a much higher 30 pressure for the charge on the grid 19.

In this secondary circuit, including the secondary winding 18 of the transformer, the grid 19 of the amplifying tube 20 and and the filament 21, is a condenser 22 and 35 a high resistance 23 in multiple shunted across the secondary of the transformer. The action of this condenser 22 is to "clear out" or demagnetize the core of the transformer more rapidly, thereby making it 40 more susceptible to rapid alternating currents. This, of course, improves the transmission of the audible frequencies, or voice frequencies. In addition to this function, it tends to keep clear, or fully discharge 45 the grid, at the point of neutrality or zero value of the E. M. F. and current. This latter action makes for "clearness" or distinctness of the voice frequencies. Again, high frequencies, such as internal tube os- 50 cillations, static and other foreign dis- turbing currents find a path of small re- sistance through the condenser 22 and the currents of high voltages with high fre- 55 quencies find a path of small resistance through the high resistance 23. Thus the condenser and high resistance offer a path of small impedance through this shunt, without causing undesired changes in the amount of charge on the grid impressed by 60 the incoming waves. High frequencies heretofore caused by oscillating tubes, are completely shunted out of the grid by this shunt, thus making it possible to employ as many tubes as desired, and to employ a much higher ratio of transformation than

has heretofore been used. The cycle of events is carried on through additional transformers and tubes as the figure shows. The capacity of the condenser, in any given apparatus, should be determined by and in proportion to the reactance due to the inductance of the transformer, it being known in the art that a step-up transformer for audio-frequency possesses a high degree of reactance. As many as seven tubes and six 75 transformers have been successfully employed without internal oscillations, and a very high degree of amplification of frequencies characteristic of the voice frequencies, attained. 80

A condenser 24, associated with a resistance 25, in each of the intermediate circuits, affords a path of low resistance for static and other waves of high frequency. This condenser, furthermore, affords a path 85 of low resistance for waves of high frequency such as are produced by "static" and other extraneous sources which are, therefore, shunted away from and hence cannot pass through the proximate high-reactance primary winding. Such a condenser, as 17, shunted across the primary winding of a transformer, likewise operates to accumulate these high-frequency waves and thus exclude them from said primary winding. 90 95

Having described my invention, what I claim and desire to secure by Letters Patent is:

1. A thermionic amplifier combined with means for preventing inherent oscillations 100 in the grid circuit thereof, comprising a high reactance and a condenser shunted across the filament-grid circuit.

2. A radio apparatus having a thermionic amplifier and containing means for preventing inherent oscillations in said amplifier, including an audio-frequency step-up transformer and a condenser disposed between said amplifier and said transformer and shunted across the filament-grid circuit of 110 the apparatus for accumulating the entire static charge of negative electricity developed by said amplifier, the ions and the grid of said amplifier constituting a conductive path communicating with said condenser. 115

3. A radio apparatus having a three-electrode thermionic amplifier and means for preventing inherent oscillations in the filament-grid circuit thereof, including a step-up transformer and, between the secondary 120 winding of said transformer and the amplifier, a current-qualifying shunt extending across the filament-grid circuit.

4. A radio apparatus having thermionic amplifiers, and including a shunting condenser extending across one grid circuit for preventing oscillations in one amplifier, and another shunting condenser arranged in multiple with a resistance extending across another grid circuit for preventing oscillations. 130

- tions in another amplifier, and affording a path of low resistance for high-frequency currents.
5. An audion receiving system having an ordinary amplifier, the grid of said amplifier being included in a circuit upon which the received oscillations are impressed, and means for preventing undesired oscillations in said grid circuit, comprising a condenser having a capacity so proportioned to the capacity of the grid as to receive and retain the ionically produced charges which tend to accumulate on said grid.
6. An audio receiving apparatus having a plurality of thermionic amplifiers and an input and an output, and means in the filament-grid circuits of said amplifiers for preventing undesired, amplified and audible internal oscillations from affecting said output.
7. An apparatus for amplifying and clarifying waves of audible frequency, including a receiving circuit containing the primary winding of a step-up transformer, a second circuit containing the secondary winding of the same transformer in which the wave frequency is the same as the wave frequency in said primary winding, a grid in the same circuit as said secondary winding, a filament, a plate and a telephonic receiver in another circuit, said grid being appropriately disposed between said filament and said plate, and a condenser short-circuited across said second circuit and co-operating with the said transformer to prevent inherent oscillations in the filament-grid circuit.
8. An apparatus for amplifying and clarifying waves of audible frequency, including a circuit containing a high reactance, a grid and a filament in series, another circuit containing said filament, a plate and a telephonic receiver, and a condenser short-circuited across the filament-grid circuit.
9. An audio amplifying apparatus having means for quieting the amplifying element, said apparatus including a source of energy, a plate arranged to attract ions from said source, a grid appropriately disposed between said source and said plate, and a high reactance in circuit with said grid and said source, said means being additional to said source and said grid, and arranged to receive the entire static charges of electricity developed by said source.
10. An audio receiving apparatus having a plurality of thermionic amplifiers and an input and an output, and means in said apparatus for preventing undesired, amplified and audible internal oscillations from affecting said output.
11. An apparatus for amplifying and clarifying waves of audible frequency, including a receiving circuit containing the primary winding of a step-up transformer, a second circuit containing the secondary winding of the same transformer in which the wave frequency is the same as the wave frequency in said primary winding, a grid in the same circuit as said secondary winding, a filament, a plate and a telephonic receiver in another circuit, said grid being appropriately disposed between said filament and said plate, and a condenser and a resistance arranged in multiple therewith, short-circuited across the filament-grid circuit and operating to prevent inherent oscillations in the filament-grid circuit.
12. A thermionic amplifier combined with means for preventing inherent oscillations therein, including a high reactance and a condenser and a resistance in multiple shunted across the filament-grid circuit.

In witness whereof, I have hereunto set my hand and affixed my name this 21st day of September, 1922.

HENRY M. WILLIAMSON.
